UNITED STATES PATENT OFFICE.

WALTER W. BURNS, OF GREENPORT, NEW YORK, ASSIGNOR TO A. B. FARQUHAR COMPANY, LIMITED, OF YORK, PENNSYLVANIA, A LIMITED PARTNERSHIP OF PENNSYLVANIA.

LINING FOR COMBUSTION CHAMBERS.

Application filed October 16, 1926. Serial No. 142,128.

This invention relates to metallic lining for the fire or combination chambers of boilers and the like.

A primary object of this invention is the provision of an improved metallic lining for combustion chambers of boilers and the like wherein the outer shell is protected in an improved way to prevent the heat from within from having a destructive effect.

Another object of my invention is the provision of a lining for combustion chambers of boilers and the like comprising sections provided with flanges extending to the outer shell of the chamber to hold the lining sections a substantial distance therefrom.

Another and further object of my invention is the provision of a lining for combustion chambers of boilers and the like comprising sections having overlapping portions and each section being provided with a flange extending its axial length for contact with the outer wall of the chamber, thereby forming a series of separate chambers between the lining and the outer wall.

Other and further objects of my invention will be apparent to those skilled in the art from a reading of the complete specification and claims.

The solution of the problem of finding a suitable lining for combustion chambers of boilers and particularly that type which is mounted on wheels and portable has long been sought. The intense heat when no lining is employed, causes the outer shell of the combustion chamber to become burned and after a time, holes appear and major repairs become necessary. In order to overcome this condition, various linings have been made with more or less success.

The distinguishing feature of the present invention is that flanges are provided on the metallic lining sections which flanges divide the space between the lining and the outer shell of the chamber into sections which are practically dead gas spaces.

Referring to the drawing wherein I have illustrated a preferred embodiment of my invention,

Figure 1 is an end view of a boiler combustion chamber showing my improved lining in place, the closure member of the combustion chamber being removed to show the interior construction.

Fig. 2 is a cross section on the line 2—2 of Fig. 1.

Fig. 3 is an enlarged edge view of one of the sections.

Fig. 4 is a plan view of the section shown in Fig. 3.

Similar reference characters refer to the same or similar parts throughout the several views of the drawing.

10 designates the outer wall of the combustion chamber of the boiler 11.

The general shape of my improved lining, as a whole, is that of a cylinder, flattened at the top, in a horizontally disposed boiler, this flattened portion being provided to protect that portion of the boiler above the water line. The lining is divided into a series of 65 complementary sections arranged about and within the lower portion of the outer wall of the combustion chamber. These sections I have designated by the numeral 13. At the top, I have provided flat sections, preferably 70 two in number, which sections complete the cylindrical portion of the lining. I have designated these sections respectively by the numerals 14 and 15.

Each section of the lining is provided with 80 an overlapping portion as at 13^a, 14^a, 15^a, shaped and in position to overlap the adjacent edge of the next lining section in such a manner as to have the inner surfaces of adjacent sections meet practically at a line, the overlapping portions being provided to close the spaces between adjacent sections and permit 85 of greater variations in the positions of the bolt holes during construction and to permit the use of sections having slight variation in 90 form.

A distinguishing feature of my lining is that to space the lining from the wall of the chamber, I provide spacing flanges designated at 13^b, 14^b and 15^b. These flanges are 95 preferably arranged, one for each section and placed adjacent the edge of a section, there being preferably though not necessarily, one flange for each section. The exact angle which the flange as a whole makes to the lining section is not essential. It may be made at such an angle as is convenient for the pattern to be drawn from the mould.

In order to hold the sections in place and 100 keep the flanges of the respective sections 105 against the outer wall of the combustion

chamber, I have provided bosses 13^c, 14^c, 15^c which are integral with the lining sections and are cast around bolts 13^d, 14^d, 15^d respectively. These bolts pass through suitably spaced holes in the shell of the combustion chamber and are held in position by suitable nuts, as shown.

In the embodiment herein illustrated, I have shown a single supporting flange 13^b, 14^b, 15^b for each respective section adjacent the respective overlapping portions 13^a, 14^a, 15^a. In this way only one supporting flange is necessary for each section since one overlapping flange acts as a support for its own section and also the adjacent section.

Each section is perforated at intervals throughout its body portion with small holes as for example holes three-eighths of an inch in diameter and one and one-half inches apart.

The construction which I have described forms sectional spaces between the lining and the outer wall of the combustion chamber. I have found that this space should be greater than the thickness of the lining body and that the supporting flanges 13^b, 14^b and 15^b should be of greater depth in a direction from and to the axis of the combustion chamber, than its thickness. In this way, sufficient heat is not conducted to the wall of the combustion chamber to do any harm.

These supporting flanges have a tendency to divide the accumulation of ashes in the space between the lining and combustion chamber wall into several parts. This permits of a less frequent cleaning of the space between the lining and the outer wall of the combustion chamber and a longer life to the lining sections at the bottom.

In practice it has been found that the long supporting flange is easy to fit into its place and its length gives it stability and decreases liability of breakage.

While I have illustrated and described in detail an embodiment of my invention, I desire to have it understood that I do not limit myself to the exact showing and that modifications and changes may be made without departing from the spirit of my invention and within the scope of the appended claims.

Having described my invention what I claim is:

1. A lining for combustion chambers of boilers and the like comprising sections, supporting flanges projecting from the respective sections and extending substantially the length of the sections, the sections extending about the combustion chamber, the flanges dividing the space between the lining and outer combustion chamber wall into sections, the space between the lining and outer wall being greater than the thickness of the lining.

2. A lining for combustion chambers of boilers and the like comprising sections, supporting flanges projecting from the respective sections and extending substantially the length of the sections and having their edges in contact with the combustion chamber wall, the flanges dividing the space between the lining and outer combustion chamber wall into sections, the proportions of the supporting flanges being such as to space the lining from the outer wall of the combustion chamber a greater distance than the thickness of the flange. 75

3. A lining for combustion chambers of boilers and the like, comprising sections provided with portions overlapping adjacent sections, supporting flanges projecting from the respective sections and extending substantially the length of the sections, the flanges dividing the space between the lining and outer combustion chamber wall into sections, the proportions of the supporting flanges being such as to space the lining from the outer wall 80 of the combustion chamber a greater distance than the thickness of the flange. 85

4. A lining for combustion chambers of boilers and the like comprising sections, adjacent sections having overlapping portions, a supporting flange for each section and located adjacent the overlapping portion, the supporting flanges extending substantially the length of the sections and dividing the space between the lining and other combustion chamber wall into sections, the proportions of the supporting flanges being such as to space the lining from the outer wall of the combustion chamber a greater distance than the thickness of the flange. 90 95

5. A lining for combustion chambers of boilers and the like comprising sections, supporting flanges projecting from the respective sections and extending substantially the length of the sections, the flanges dividing the space between the lining and outer combustion chamber wall into sections, the area of the contacting line between the flange and outer wall being small compared to the cross section of the space between the lining and the outer wall. 105 110

6. A lining for combustion chambers of boilers and the like comprising sections, overlapping portions extending from each section adjacent its neighboring section, a supporting flange extending from the body of each section adjacent the overlapping portion, the supporting flange extending substantially the length of the section and means for holding the sections in place within a combustion chamber. 115 120

In testimony whereof I hereunto affix my signature.

WALTER W. BURNS.
